UNITED STATES PATENT OFFICE.

ARCHIE B. CONRAD, OF PHILADELPHIA, PENNSYLVANIA.

AUXILIARY AIR-INLET DEVICE FOR INTERNAL-COMBUSTION ENGINES.

1,164,576.

Specification of Letters Patent. Patented Dec. 14, 1915.

Application filed April 10, 1914. Serial No. 830,991.

To all whom it may concern:

- Be it known that I, ARCHIE B. CONRAD, a citizen of the United States of America, residing at Philadelphia, in the county of 5 Philadelphia and State of Pennsylvania, have invented new and useful Improvements in Auxiliary Air-Inlet Devices for Internal-Combustion Engines, of which the following is a specification.
- 10 This invention relates to an auxiliary air inlet device for internal combustion engines particularly to that class used in conjunction with the carburetors on internal combustion engines, to lessen the quantity of 15 fuel consumed and in other ways to increase the efficiency of the engine.

It is a well known fact that it is practically impossible to set a carburetor in such a manner that its adjustment will be correct 20 for all speeds of the engine with which it is associated. Thus, when set for a relatively slow speed of the engine it is out of adjustment for considerably higher speeds thereof.

The object of this invention is to provide 25 a device which operates simultaneously with the throttle of the carburetor and with the resultant change in speed of the engine, and which increases the proportion of air in the fuel mixture, supplied to the cylinders, upon 30 an increase in the speed of said engine.

Another object is to provide such a device comprising a simple construction and adapted to be operated by the same means, that operates the throttle, that is, either 35 foot or hand lever.

A further object is to provide a device of 40 this character which can be readily attached either to a central portion of the manifold, or to the connection between the carburetor and the manifold.

Further objects and advantages are hereinafter brought out in the following specification when read in conjunction with the accompanying drawings, in which:

45 Figure 1 is a side elevation of the preferred embodiment of the invention; Fig. 2 is a front elevation of the same; Fig. 3 is a vertical sectional view of the line 3—3 of Fig. 2, showing the device coupled to the 50 connection between a carburetor and a manifold. Fig. 4 is a detailed view on the line 4—4 of Fig. 1; and Fig. 5 is a sectional view on the line 5—5 of Fig. 3.

Referring to the drawings, the invention 55 in its preferred embodiment, comprises a globular shaped body 1, having a threaded opening 2 at the top, and an extension 3 at

one side, provided with central opening 4 and threaded upon its outer side 5, while the bottom of said body is provided with an enlarged threaded opening 6, adapted to receive a removable frame 7, comprising substantially circular side walls 8 surrounded by a flange 9 adapted to bind against the lowermost edge of the body 1 when said frame is screwed into the opening 6. Said frame 7 is further provided with a central opening 15 in its lower end walls through which slidably passes a shaft or pin 16, while the side walls 8 are provided with oppositely disposed openings 17 for the free admission of air, and one or more additional openings 18, intermediate the opening 17, and adapted to receive the enlarged portion 19 of an angularly bent lever 20. Said lever 20 is bifurcated at its inner end and adapted to partially surround the pin 16 and bear against the collar 22, secured upon said pin, while the outermost end of said lever is enlarged and provided with an eye 23 to receive a chain, link, or other suitable connection with a desired actuating means. Said lever is pivotally mounted upon a pin 24, passing centrally through the enlarged portion 19 and journaled at 25 in the side walls 8 of the frame 7. A modified form of lever may be mounted as shown by the dot-and-dash lines in Figs. 1 and 2.

Substantially intermediate of the length of the pin 16 are secured a nut 30 and valve disk 31, the latter being circular and beveled upon its peripheral edge portion to coöperate with the beveled seat 32 of the uppermost edge of the frame 7. Also surrounding the pin 16 is an adjustable sleeve 33, provided with a head 34 by which the same is turned, said sleeve being threaded upon its outer face 35, and adapted to engage the internally threaded opening 2 of the body 1, and to compress a helical spring 36 against the upper surface of the valve disk 31. A second spring 37 is compressed between the collar 22 and the nut 30, the spring 36, however, being much stronger and acting in such manner as to positively seat said valve 31.

In Fig. 3 is illustrated any desired form of carburetor 40 with the usual adjustable air inlet 41, fuel inlet 42 and combustible mixture outlet 43, said outlet being connected by the hollow section of pipe 44 to the Y 45, the branches of said Y leading to the respective cylinders of an internal combustion engine. The section 44 is shaped in any convenient manner to receive the exten-

sion 3 from the body portion 1 of the device and embodying the present invention.

In the operation of the device above described, the throttle 46 on the carbureter 5 and the lever 20 of the economizer are preferably connected together and to the same speed operating lever of the machine. As the speed of the engine increases, and it is necessary to admit a greater amount of air 10 into the manifold in proportion to the amount of fuel gas admitted, the lever 20 is operated in the direction of the arrow, thus pressing upwardly upon the spring 37, which relieves or equalizes a portion of the 15 downward pressure of the spring 36 upon the valve disk 31, whereupon the vacuum in the cylinders, and therefore in the manifold, acts to raise said valve and admit a definite additional amount of air to maintain the desired richness of the fuel mixture. 20 As is evident from the drawings the position of the sleeve 33, and therefore the tension of the spring 36 upon the valve disk, is variable and is adjusted by revolving said sleeve 25 in the proper direction.

For the purpose of increasing the ease with which an engine provided with this device can be started, any desired amount of fluid, either liquid or gas may be admitted, by way of the nipple 48, through the lower-most portion of the body 1, and thence through the capillary bore 49 into the body 1, said bore terminating in the valve seat 32 so that it is opened simultaneously with the opening of the air passage in the said body 1. It is to be noted that this auxiliary opening through the nipple 48 and bore 49 may also be used for the admission of various forms of fluids for counteracting or cleaning the carbon deposit from the engine cylinders, for lubricating said cylinders, for supplying pure oxygen to increase the efficiency of the engine, and for various other uses. In this connection 45 it should be noted that in the event of the fuel supply to the carbureter being clogged or otherwise made inoperable, it is possible to continue the running of the engine by supplying the fuel, generally gasolene, 50 through the nipple 48 and through the body 1 into the engine cylinder by way of the usual manifold and other connecting channels.

While I have described but one form in which this invention may be embodied it is 55 obvious that numerous changes may be made therein without departing from the spirit of the invention or the scope of the appended claims.

What I claim is:—

60 1. In combination with the manifold of an internal combustion engine, a device comprising a hollow body having a threaded

opening in the upper and lower portions thereof, a frame threadedly connected with the lower threaded opening of said body and 65 formed with a valve seat, a rod passing vertically through said body and frame, a valve disk, a spring tensioning device threadedly connected in the upper opening of the body, resilient means embracing said rod and disposed within said body and interposed between one face of the valve disk and the said 70 spring tensioning device for seating said valve, an opening from said body in the manifold, a collar carried by said rod, another spring tensioning device carried by said rod and disposed within said frame, a second adjustable resilient means embracing said rod and interposed between one face of the collar and the opposite face of the 75 last mentioned spring tensioning device, a lever co-acting with the opposite face of the collar for operating said valve, a throttle valve, and a rod connecting the lever with said throttle valve, whereby the tension of 80 the second resilient means is altered in accordance with the position of the throttle valve.

2. In combination with the manifold of an internal combustion engine, a device 90 comprising a hollow body having a threaded opening in the upper and lower portions thereof, a frame threadedly connected with the lower threaded opening of said body and 95 formed with a valve seat, a rod passing vertically through said body and frame, a valve disk, a spring tensioning device threadedly connected in the upper opening of the body, resilient means disposed within 100 said body and interposed between one face of the valve disk and a spring tensioning device for seating said valve, an opening from said body in said manifold, a collar carried by said rod, another spring tensioning device carried by said rod and disposed within 105 said frame, a second adjustable resilient means interposed between one face of the collar and the opposite face of the last mentioned spring tensioning device, a lever pivotally mounted in the side walls of 110 the frame at a point below said last named spring tensioning device and co-acting with the opposite face of the collar for operating said seat valve, a throttle valve, and a rod connecting the lever with such throttle 115 valve, whereby the tension of the second resilient means is altered in accordance with the position of the throttle valve.

In testimony whereof I affix my signature in presence of two witnesses.

ARCHIE B. CONRAD.
